UNITED STATES PATENT OFFICE.

EDWARD TIMBS, OF LOS ANGELES, CALIFORNIA, ASSIGNOR TO THE NATIONAL SUPPLY COMPANY, OF TOLEDO, OHIO, A CORPORATION OF OHIO.

BAR LATCH FOR SPRING CASING HOOKS.

Application filed May 25, 1926. Serial No. 111,624.

This invention relates to a bar latch for spring casing hooks and especially to a bar latch for that type of hooks employed in the construction and operation of oil and gas wells for supporting the casing, drill pipe and the like during the drilling operation of the well.

In the construction of oil and gas wells, the casing or drill stem and drill employed is customarily suspended by a hook. This casing or drill stem or drill assembly consists of a plurality of sections of drill stems connected together with the drill secured to the bottom of the assembly and during the construction and operation of oil and gas wells, it frequently becomes necessary to add or remove one or more sections of the casing or drill stem. This is accomplished by rotating the casing or drill stem at one point below the point where the same is broken by means of what is commonly termed a rotary table, while tongs or the like are placed upon the casing or drill stem above the joint to hold the sections to be removed stationary. Suitable means are provided for removing the disconnected section of drill stem from the remainder of the drill stem after breaking the connection between the said sections. The said sections are rotated relative to each other, with the result that the connecting threads will be damaged. Accordingly, the hook, as customarily employed for supporting the casing or drill stem, is generally provided with a spring which is adapted to pick up and elevate the disconnected section which has been disengaged from the remaining section of the drill stem.

It is therefore an object of this invention to provide latch means for latching or locking the hook proper relative to the supporting bails so as to prevent rotation of the hook relative to the bails, and which lock or latch means are easily disengageable when it is desired to rotate the hook to any particular position during the drilling operation.

Another object of this invention is to provide a bar latch which is adapted to be inserted between the bails which support the hook and through the spring hook shank cap and which cap provides means for releasably latching the said bar in position so as to prevent rotation of the hook shank relative to the bails.

Other objects and advantages of this invention will be apparent from the following detailed description of a preferred embodiment thereof as illustrated in the accompanying drawings, in which drawings:

60

Figure 1 is a side elevation partly in vertical mid-section of a casing hook and illustrating a bar latch as provided therefor embodying this invention.

Figure 2 is a top plan view thereof taken substantially on the line 2—2 of Figure 1.

In the preferred embodiment of this invention, illustrated in the accompanying drawings, 1 illustrates a link which is adapted to be secured to the rotary hoist cable in any desired or preferred manner, and which link 1 has downwardly extending bails 2 as terminating in eyes 3. Journalled in the eyes 3 is a swivel bearing block 4 having a bore 5 formed therethrough in which a sleeve 6 is inserted. The sleeve 6 is supported on the bearing block 4 at an annular shoulder 7.

The hook 8, which may be of any desired form, is provided with a shank 9 which extends through the sleeve 6 and is provided at its upper end with a spring hook shank cap 10 screw-threaded to the end of the shank 9 as illustrated at 11 and is provided with a cylindrical portion 12 of substantially the same exterior diameter as the interior diameter of the sleeve 6 at 13. A bearing washer 14 is slidably mounted on the shank 9 below the cylindrical portion 12 of the cap 10 so as to provide a bearing between the shank 9 and the sleeve 6 as the shank 9 moves longitudinally in the sleeve 6. The sleeve 6 is at its lower end formed with a shoulder 15 and is at 16 of substantially the same interior diameter as the exterior diameter of the shank 9 so as to provide a bearing for the shank 9 at the lower end of the sleeve 6. A helical spring 17 surrounds the shank 9 and engages at one end the shoulder 15 and at its opposite end the lower face of the bearing washer 14 so as to normally hold the spring 17 and the hook 8 in the position illustrated in Figure 1, except when the hook 8 is provided with a large load sufficient to compress the spring 17 and when a section of the drill stem is disconnected from the remaining portion of the drill stem, the spring will operate to raise the said section from the remainder of the drill stem, preventing engagement of

the threads and when the section is released, it is essential that means be provided for preventing rotation of the hook 8 relative to the bails 2 so as to permit the bar 18 to 50
5 rotate during the expansion of the spring 17, which might result in the throwing of the drill stem around in the derrick so as to cause a serious accident or so as to strike some object and to cause considerable damage 55
10 to the section of drill stem being removed.

For the purpose of preventing relative rotation of the hook 8 and the link 1, I prefer to employ a bar 18 which is provided at one 55
15 end with a chain 19 which may be secured to the cap 10 or to the bail 2 as desired, and which chain 19 is of sufficient length so as to permit the manipulation of the bar 18 and its insertion into a bore 20 formed in 60
20 the cap 10 so that the bar 18 projects between the opposite bails 2 of the link 1, thus preventing relative rotation of the hook 8 and the said link 1.

In order to hold the bar 20 in position and 65
25 so as to permit the same to be easily removed, the following preferred latch means are provided:

The cap 10 is bored out as illustrated at 70
21 and a ball 22 is mounted in the end of 75
30 the bore in position to engage the cut away portion 23 of the latch bar 18 and a compression spring 24 is mounted in the bore 21 in position to yieldably urge the ball 22 toward the cutaway portion 23. In order to 80
35 retain the spring 24 in position, a plug 25 is screw-threaded in the outer end of the bore 21 and the tension which is exerted by the spring 24 against the ball 22 may be regulated by the screw-threading of the plug 40
45 25 into the bore 21.

It will be obvious from the foregoing, that I have provided a simple positive means which may easily be released for latching or locking the hook 8 upon rotation relative to the link 1.

Having fully described a preferred embodiment of my invention, it is to be understood that I do not wish to be limited to the exact details of construction herein set forth

which may obviously be varied without departing from the spirit of my invention as set forth in the appended claims.

I claim:

1. In a rotation lock for well casing hooks, the combination of a bar, a cap having a transverse bore formed therethrough and into which the bar is adapted to be inserted, spring latch means for releasably holding the bar in the said bore, and which bar extends from the opposite ends of the said bore to be engaged between hoisting bails which are secured to the body of the said hook.

2. In a rotation lock for well casing hooks, the combination of a bar, a cap having a transverse bore formed therethrough into which the said bar is adapted to be inserted, the said cap being secured to the shank of the said hook, spring latch means for releasably holding the said bar in the said bore, and which bar extends from the opposite ends of the said bore to be engaged between hoisting bails secured to the body of the said hook.

3. In combination with a well casing hook, comprising a hook having a shank, a body, spring means yieldably supporting the said hook on the said body, and hoisting bails secured to the said body, of a bar, a cap secured to the shank of the said hook and having a transverse bore formed therethrough into which the said bar is adapted to be inserted, and spring latch means for releasably holding the said bar in position within the said bore between the said bails.

4. In a rotation hook for well casing hooks, the combination of a bar, a cap having a transverse bore formed therethrough and into which the bar is adapted to be inserted, the said cap being secured to the said hook, spring latch means for releasably holding the bar in the said bore between the hoisting bails of the hook, and a flexible connecting member connecting one end of the said bar with the said hook.

Signed at Torrance, Calif., this 13 day of May, 1926.

EDWARD TIMBS.
